UNITED STATES PATENT OFFICE

2,383,852

WINDOW CONSTRUCTION

Harry Goldenberg, Philadelphia, Pa., assignor of
one-third to Henry Goldenberg and one-third
to Charles E. Meyers, both of Philadelphia, Pa.

Application October 6, 1943, Serial No. 505,101

5 Claims. (Cl. 20—46)

This invention relates to window constructions and more particularly to certain improvements in the construction of double-hung sliding sash windows of the type described and claimed in my prior United States Letters Patent No. 2,221,515, granted November 12, 1940.

Among the principal objects of the present invention is to provide a double-hung sliding sash window construction wherein provision is had for readily swinging either or both of the sashes inwardly of the window frame so as to render both sides of the glass panes of the window sashes accessible from within the room for cleaning.

A further object of the present invention is to provide a window construction of the above type wherein either or both of the sliding sashes may not only be swung inwardly of the window frame but may also be quick-detachably removed therefrom with a minimum of effort and without requiring any disorganization of the sash-balancing mechanism, the latter remaining intact within the vertical boxes provided therefor in opposite sides of the window frame, the arrangement being such that either one of the sashes may be entirely removed from the window frame independently of the other sash.

A further object of the present invention is to improve the design and construction of the means employed for locking the sash-balancing mechanisms in position preliminarily to removal of the sashes from their frames or to the swinging thereof inwardly about their respective pivots, these locking means being automatically operative upon both sides of each sash to hold the sash-balancing mechanisms in locked position and so render the sash free to be either bodily removed from its frame or swung inwardly about its pivots, as may be desired. Additionally, this improved locking means for the sash-balancing mechanism is so designed that automatically as the sash is fitted in its frame for vertical movement therein, the sash-balancing mechanisms are released from their locked positions and become attached to the sash for operation therewith in the conventional manner.

Still other objects are to so simplify the construction of the window unit as a whole that it may be readily and economically manufactured and installed in new as well as in existing buildings; to provide means whereby access is readily had to the sash-balancing weights, when the same are employed, without requiring difficult dismantling of the window frame as is now required in the conventional type of window construction; to make possible the use of any con-

ventional type of sash-balancing means; and to generally improve the construction of the window unit of my previously issued patent aforesaid.

Other objects and advantages of the invention and economies effected thereby will be apparent more fully hereinafter, it being understood that the invention consists substantially in the combination, construction, location and relative arrangement of parts, all as will appear more fully hereinafter, as shown in the accompanying drawings and as finally pointed out in the appended claims.

In the accompanying drawings:

Figure 1 is a front elevational view of the window unit constructed in accordance with and embodying the principles of the present invention, the upper and lower sashes both being shown in closed position;

Figure 2 is a front elevational view showing the lower sash swung out of the plane of the window frame toward the inner or room side thereof;

Figure 3 is a view similar to Figure 2 but showing the upper sash in lowered position;

Figure 4 is a view showing both of the sashes swung inwardly of the window frame;

Figure 5 is a vertical sectional view taken along the lines 5—5 of Figure 1;

Figure 6 is a vertical sectional view corresponding to Figure 5 but showing the lower sash removed and the upper sash in lowered position;

Figure 7 is a vertical sectional view taken along the line 7—7 of Figure 1;

Figures 8, 9 and 10 are transverse sectional views taken respectively along the lines 8—8 of Figure 1, 9—9 of Figure 2 and 10—10 of Figure 4;

Figures 11 and 12 are front and side elevational views, respectively, of the locking detents for the sash-balancing devices;

Figures 13 and 14 are transverse sectional views taken respectively along the lines 13—13 and 14—14 of Figures 11 and 12;

Figure 15 is a front elevational view of the lower portion of one side of the window frame showing the lower sash swung out of the plane of the frame and its sash-balancing device secured by a locking detent;

Figures 16 and 17 are side and rear views (partially in section) of the locking detent per se;

Figures 18 and 19 are views respectively corresponding to Figures 5 and 7 but with the sashes removed from or swung out of the plane of the window frame;

Figure 20 is a perspective view of a window

ventilator designed for use with the unit of the present invention;

Figure 21 is a vertical sectional view of said window ventilator;

Figure 22 is a partial elevational view of one of the sash retaining elements;

Figure 23 is a vertical sectional view of said sash retaining elements taken on the line 23—23 of Figure 22;

Figure 24 is a view similar to Figure 23 but showing the detent lifted to permit removal of one of the sash retaining elements; and

Figure 25 is a transverse sectional view taken on the line 25—25 of Figure 2.

Referring now to the drawings, it will be observed that the window frame of the present invention which may be formed of wood or metal and of any height and width as may be desired, is generally of rectangular form having a bottom sill member 10, a top header member 11 and a pair of opposed vertical stiles 12 and 13, all of which are joined together in any suitable manner. As appears most clearly in Figures 5 to 7, the inner faces of the vertical stiles 12 and 13 are correspondingly shaped as shown to provide laterally spaced runways which are respectively adapted to slidably receive the sliding sashes 14 and 15 of the window. It will be noted particularly that the outer sliding sash 14 is of less width than the inner sash 15, the purpose of which will appear hereinafter. Provided in each of the stiles 12 and 13 are a pair of laterally spaced vertical boxes 16 and 17 in which are disposed the sash-balancing mechanisms of the type preferably employing a coarse pitch screw 18 which moves axially into and out of an elongated tube immovably fixed in the upper part of the frame against the action of a spirally wound sash-balancing spring encased within said tube. Inasmuch as this type of sash-balancing mechanism is of conventional construction and quite generally used in the art, no further description thereof need be given here, it being understood further that the present invention is, of course, not limited to the use of this type sash-balancing mechanism and that in lieu thereof, the conventional weighted sash cords extending over pulleys fitted in the vertical stiles 12 and 13 may be employed. These pulleys are shown dotted in Figures 5, 6 and 7.

It will be noted that except for the fact that the outer sash 14 is of less width than the inner sash 15, these sashes may be of conventional construction, although preferably, the lower rail member 14^a of the outer sash and the upper rail member 15^a of the inner sash are respectively provided with complementally shaped rabbeted edges to provide an adequate weather tight fit between these meeting rails of the two sashes when the same are both brought into the closed position as shown in Figures 1 and 5. Also, the upper rail 14^b of the outer sash is preferably rabbeted to snugly fit a complementally rabbeted part of the top header member 11 of the window frame. In order to compensate for slight difference in widths of the outer and inner sashes and to present the double-hung sash window unit of the present invention with a more or less conventional appearance, the opposed vertical rails of the outer sash 14 are each of less width than the corresponding vertical rails of the inner sash 15, thereby providing both sashes with light openings of equal width, as is shown most clearly in Figure 1.

The vertical stiles 12 and 13 of the window

frame are each so constructed as to be of stepped formation in their transverse sections (see Figures 8 to 10), this stepped cross-section of each stile being of gradually reduced width from the outer toward the inner sides of the frame. Thus, each of the stiles 12 and 13 is provided with the laterally off-set vertical faces 19, 20 and 21, these faces being separated from each other by the intervening boxes or channels 16 and 17 in which are operable the sash-balancing devices of the screw type hereinbefore mentioned.

Adapted to be respectively secured to the several off-set faces 19, 20 and 21 of each of the vertical stiles of the window frame are the vertically extending members 22, 23 and 24. Of these members, those designated 22 and 24 constitute the outer guide or channel strips for the sliding sashes 14 and 15, while the intermediate member designated 23 serves as the parting strip between the sliding sashes. For purposes which will be apparent hereinafter, one of each pair of the sash guiding and retaining members 23—23 and 24—24 is split at points intermediate the length thereof so as to permit the removal, when desired, of the lower sections of these members, and in this connection, it will be understood that, if desired, members 22 and the fixed sections of the split members 23 and 24 may be formed as integral parts of the vertical stile with which they are associated.

A typical construction of the split sash guiding and retainer members 23 and 24 is shown in Figures 22, 23 and 24, wherein it will be observed that each of these members is composed of a pair of vertically aligned sections 25 and 26, the upper section 25 being adapted for permanent securement to the vertical stile of the window frame, while the lower section 26 is adapted to be quick-detachably removed from the stile as desired. The vertically aligned sections 25 and 26 have their meeting edges 27 and 28 disposed at elevations sufficiently above the lowered sashes with which they are respectively associated when the sashes are in their lowered positions, so that when the lower section 26 of a split retaining member for a given sash is removed, the said given sash may then be swung freely out of its normal plane of sliding movement.

As most clearly appears in Figures 1 to 7, inclusive, the left-hand retaining member for the outer sash 14, when the window is viewed as shown in Figure 1, is split as at 29 to provide an upper fixed section 25^a and the lower removable section 26^a. The corresponding right-hand retaining member 23 is continuous for the full length of the window frame. On the other hand, the right-hand one of the retaining members 24—24 for the inner sash 15 is split as at 30 to provide a fixed upper section 25^b and a removable lower section 26^b. It will be observed that the split 30 in the retaining member 24 is at an elevation just above the upper edge of the inner sash 15 when the latter is in its lowered position, while the split 29 in the retaining member 23 is at an elevation just above the upper edge of the outer sash 14 when the latter is in its lowered position.

It will thus be apparent that when the lower section 26^b of the retaining member 24 is removed, in the manner to be described hereinafter, the sash 15 may be swung about its left-hand pivots 30^a—30^a out of its normal plane of vertical sliding movement. Similarly, when the lower section 26^a of the inner retaining member 23 is removed, the outer sash 14 may likewise be swung

inwardly of the window frame and out of its normal plane of vertical sliding movement about its vertically spaced pivots 31—31, as shown in Figure 3.

In order to secure in position the removable lower sections of the split sash retaining members 23 and 24, a detent 32 is employed. The construction and operation of this detent is shown most clearly in Figures 22 to 24 wherein it will be observed that this detent is preferably a sheet metal plate member of generally U-shape, the leg 33 of which is slidably fitted within a slot 34 provided in the lower end of the fixed section 25 of the sash retaining member. This leg 33 of the detent is notched as at 35 to receive a transverse pin 36 carried by the section 25, this pin coacting with the notch 35 in the detent to limit the vertical movement of the latter upwardly and downwardly. The base portion 37 of the U-shape detent is adapted to be received in a slot 38 formed in the upper end of the removable section 26 of the sash retaining member, while the outer leg 39 of the U-shape detent is disposed exteriorly of the said member and serves as a handle by means of which the detent may be raised and lowered. When the detent 32 is in its lowered position as shown in Figure 23, the removable section 26 of the sash retaining member is locked in place by the depending part 40 of the detent handle part 39, while when the detent is raised into the position shown in Figure 24, the removable section 26 is free to be slipped past the detent in the direction of the arrow shown in said figure to permit removal of said section 26 from the window frame. It will be understood, of course, that the detent arrangement as shown in Figures 22 to 24 is identical for both of the split sash retaining members. In order to secure the lower ends of the removable sections 26^a and 26^b in position against unintentional displacement from the sides of the window frame, they are each slotted, as at 41, so as to adapt them to be slipped over the shank of a headed pin 41^a extending laterally from the stile of the window frame against which the removable section of the sash retaining member is removably secured in position.

As appears most clearly in Figures 1 to 10, inclusive, the outer sash 14 is fitted along its right-hand edge with a pair of vertically spaced male hinge pins 42 adapted respectively to engage with the female hinge elements 43 when said outer sash is moved into its lowermost position, as shown in Figures 3, 4, 6 and 7. Similarly, the inner sash 15 is provided along its left-hand edge with vertically spaced male hinge pins 44 which are adapted respectively to engage the female hinge elements 45 when said inner sash is lowered into its lowermost position, as shown in Figures 1 to 5.

From the foregoing, it will be observed that when either or both of the sashes 14 and 15 are lowered into their respective lowermost positions, they may be swung inwardly of the frame about their respective pivots, assuming, of course, that the removable sections 26^a and 26^b of the retaining members which respectively engage the free or unpivoted edges of the sashes are removed from the frame. Thus, if it is desired to swing the inner sash 15 inwardly, it is merely necessary to lower this sash so as to effect a pivotal connection between the hinge elements 44 and 45 and then remove the lower section 26^b of the right-hand sash retaining member 24. The inner sash may then be swung inwardly of the room, as illustrated in Figures 2, 3 and 4. Similarly, in order to swing the outer sash 14 inwardly of the

room, as shown in Figure 4, the said sash is first lowered so as to effect a pivotal connection between the hinge elements 42 and 43, following which the lower section 26^a of the sash retaining member 23 is removed, thereby permitting the sash to be swung inwardly as shown.

The pivotal connections between each sash and the window frame are such as to permit the sashes to be readily removed bodily from the frame, it being merely necessary, in order to effect this, to lift each sash sufficiently to disengage the hinge pins (which are fixed to the sashes) from the female hinge elements (which are fixed to the opposed vertical stiles of the frame). This operation of bodily removing each sash from its frame is, of course, performed when the sash is in its lowermost position, in which case the sash-balancing mechanisms heretofore mentioned are drawn into their most extended condition. By so bodily removing the sash from the window frame, it is, of course, necessary to effect its disengagement from the sash-balancing mechanisms and this is accomplished by the means now to be described.

As has been previously mentioned, each of the sash-balancing mechanisms is disposed for operation within the vertically extending boxes or channels 16 and 17 provided in each of the vertical stiles of the frame. These sash-balancing mechanisms may be of any conventional type, as hereinbefore mentioned, such as the screw type shown more particularly in Figures 11 and 12, or of the type employing weighted sash cords such as are designated by the reference numeral 46 in Figures 5 to 7 and 16 to 19, both inclusive. The sash-balancing mechanism of whichever type is employed is detachably secured to the sash by the means now to be described, it being understood, of course, that a pair of these sash-balancing devices is operatively associated with each sash.

As appears most clearly in Figures 11 to 16, inclusive, the means employed for removably securing each side of a sash to its operatively associated balancing device essentially consists of a block 47 which is slidably disposed within each of the vertically extending boxes or channels 16—16 and 17—17 provided in the side members of the window frame. To provide for ease of movement of this block 47 in its channel, the latter may be provided with a sheet metal lining such as is designated by the numeral 48 in Figures 11 to 14, the free edges of this sheet metal liner channel being inturned as at 49—49 to prevent accidental displacement of the block 47 from its channel. The upper end of the block 47 is suitably slotted or apertured, as at 50 (see Figures 16 and 17) for communication with a pocket 51 formed in the upper portion of the block, the opposite side walls of this pocket being provided with aligned openings 52—52 to receive a transverse pin 53 therethrough. In the case where the screw type sash-balancing device is employed, as shown in Figures 11 and 12, the lower end of the screw 18 thereof is projected through the opening 50 and into the pocket 51 of the body member 47 wherein it is secured by the transversely extending pin 53. Where the weighted sash cord balancing mechanism is employed, as shown in Figures 16 and 17, the free (unweighted) end of the cord 46 is projected through the end opening 50 and then knotted as at 54 in such manner as to permit the knotted end to be packed into the socket 51.

The body member 47, as most clearly appears in Figures 11 to 16, is provided with an integrally

formed element 55 which projects frontally of the body member and into the path of sliding movement of the sash, this element being adapted for reception within a notch formed in the side edge of the sash. Inasmuch as a pair of the sash connecting members 47 is employed in connection with each sash, it will be understood that each sash is provided with a pair of notches for respectively receiving the projecting elements 55. Thus, as shown in Figures 2 and 3, the inner sash 15 is provided with a pair of such notches designated 56-56, while the outer sash 14 is similarly provided with a pair of notches 57-57. The notches 56-56 in the opposite sides of the inner sash 15, and the similar notches 57-57 in the opposite sides of the outer sash 14, so respectively coat with the projecting elements 55 of the members 47 which are respectively disposed for sliding movement in the channels 16-16 and 17-17 that when the said sashes are in their fully closed position as shown in Figures 1, 5, 7 and 8, in which position said sashes are disposed for normal sliding movement vertically within the window frame, each sash is operatively connected to its pair of sash-balancing devices. This operative connection remains intact and unimpaired so long as the sashes are disposed in their normal planes of vertical movement.

Pivotedly secured to the lower end of each of the sliding blocks 47 is a detent element 58. This detent element 58 is provided with an integrally formed head 59 which is generally wedge shaped in transverse cross-section to provide a camming surface 60 against which the edge of the sash may bear to actuate the detent element. As most clearly appears in Figures 16 and 17, the detent 58 is pivoted to the body member 47 by means of a transverse pivot pin 61. A coiled compression spring 62, disposed in intervening relation between the head 59 of the detent 58 and the relatively stationary member 47, imparts such bias to the detent as to maintain the head 59 thereof in the outwardly extended position as shown in Figure 16. In this spring-pressed position of the detent 58, its lower main body portion 62 is pressed flatwise against the inner wall of the channel in which the body member 47 is slidably disposed, as is shown more particularly in Figure 12. This depending body portion 62 of the detent element is transversely apertured as at 63 for reception of a pin or stud 64 which is secured in fixed position to the inner wall or base of the channel which receives the sliding block 47.

In the operation of the sash-detaining means just described, it will be assumed that the inner sash 15 is in its normal vertical sliding position as is shown in Figures 1, 5, 7 and 8. In this position of the sash 15, the opposite edges thereof will overlie and be in close proximity to the exposed surfaces of the sliding detainer blocks 47, and the projecting elements 55 of the latter will be received respectively in the notches 56-56 provided in the opposite side edges of the sash. Also, while the sash is in this normal position, the opposite side edges thereof will press against the heads 59 of the pivoted detent members 58 and will force the same inwardly against the normal bias of the compression springs 62, thereby rotating the body portions 62 of the detents into the dotted line position shown in Figure 12 with the result that the detent is free of the retaining pins or studs 64. The detaining blocks 47 are thus free to move with the sash 15 and being connected to the latter by means of the projecting elements 55, the sash is operatively connected to its sash-bal-

ancing devices and the latter are then operative to balance the weight of the sash in whatever position it may be located.

However, when the sash 15 is lowered into its lowermost position so that its hinge pins are in engagement with the hinge elements of the frame so as to enable the sash to be swung inwardly of the room, when the sash is so swung inwardly, its side edges not only become disengaged from the elements 55 of the sliding detainer blocks 47, but they also free the heads 59 of the detent members 58 so as to permit the latter to rotate about its pivot under the biasing influence of the spring 62. This latter action is automatic upon swinging of the sash inwardly of its normal plane of vertical movement and effects instant engagement of the apertured ends 63 with the fixed pins or studs 64 to thereby anchor the sliding blocks 47 into position as shown in Figures 11, 12, 18 and 19. The sash-balancing devices are thus held against retraction, that is, in their fully extended condition, whereby the sashes may be bodily removed from the window frame without disturbing the sash-balancing mechanisms. It will be understood, of course, that exactly the same action occurs in the case of either sash and that automatically as either sash is swung inwardly of the frame about its pivots, the sash-balancing devices are locked in position to thereby permit bodily removal of the sash, if desired, from the window frame.

To restore the sash-balancing device into operative condition, it is merely necessary to swing the sash back into its normal sliding position within the frame whereupon the projecting elements 55 of the sliding detainer blocks operatively engage the sash and connect the blocks thereto, simultaneously as the detents 58 are rotated out of engagement with their detaining pins or studs 64.

It will be understood, of course, that the device for connecting the sashes to their respective balancing mechanisms, consisting of the members 47 and 58, may be constructed of any suitable material. Preferably, these members are molded out of plastic material, although it will be understood that the present invention is not limited to the method of constructing this connecting device to the material of which it is formed.

In addition to the foregoing, the present invention has as its object a construction of window frame which provides ready access to the sash-weight boxes from the front or room side of the window frame. This construction is shown most clearly in Figures 1 to 4, inclusive, and 25. As most clearly appears in Figure 25, the opposite vertically extending members 65-65 of the frame and which extend laterally of the vertical stiles 12 and 13 to form the front panels of the sash-weight boxes are each provided in the lower portions thereof with an opening 66 (see Figure 25) through which access is had into the interior of the sash-weight boxes for removal, replacement or adjustment of the sash-weights and their supporting cords. These openings 66 are each normally closed by a closure member 67 which is so constructed as to provide a main body portion which snugly fits into the opening and which is a perimetral flange 68 which overlies the front surface of the member 65 marginally surrounding the opening 66. The flanged closure member 67 is removably secured in position, as shown in Figure 25, by a removable pin 69 which is projected through registering openings formed in the frame

69 and the closure 67. It will be apparent that upon withdrawal of the pin 69, the closure member 67 may be removed and so expose the opening in the frame member 65 for access to the interior of the sash-weight box.

Although the present invention provides for inward swinging of the sashes and bodily removal thereof from the frame, it will be apparent that when the sashes are disposed in their normal planes of vertical movement, the sashes are then slideable in the frame in the same manner as any conventionally constructed double-hung sash, and when so operated, the window of the present invention may be equipped with a screened ventilating unit such as is shown more particularly in Figures 20 and 21. This ventilating unit, which forms part of the present invention, essentially consists of a pair of side members 70—70 of generally trapezoidal shape, these members being secured together in the spaced relation shown by an inclined base member 71 and a longitudinal stretcher member 72, these latter members being secured together in any suitable manner, as at 73, and to the side members 70—70 to form a rigid unit. The frontal edges of the members 70—70 are each rabbeted or grooved, as at 74 (see Figure 20), to provide a pair of opposed channels within which are removably received the opposite edges of a glass panel 75. This glass panel 75 and the stretcher member 72 forming the lower base board for the channel are commonly disposed in a plane located inwardly of the inner sash 15 and inclined with respect thereto.

Fitted within the rear of the ventilating unit is a removable screen 76 having a rigid frame 77, the opposite edges of which are slidably fitted between the side members 70—70 of the ventilating unit, this screen being so disposed within the ventilating unit that when the latter is mounted in position as shown in Figure 21, the screen is disposed substantially in the plane of the sash 15.

It will be observed that the side members 70—70 of the ventilator unit are each provided in the bottom edges thereof with notches 78 and that these bottom edges are so shaped complementally with respect to the transverse shape of the window sill 10 to provide for a snug and secure fit of the ventilating unit upon the sill. Also, it will be observed that the upper edges of the side members 70—70 of the ventilating unit are each notched, as at 79—79, to receive the lower edge of the window sash 15 when the latter is moved downwardly into the position shown in Figure 21, it being observed that in this position, the window sash 15 is so interlocked with the window ventilator as to secure the latter in its operative position. In addition, the rear edges of the side members 70—70 of the window ventilator are notched, as at 80—80, to accommodate the lower hinge elements 43 and 45, which are respectively secured to the vertical stiles 13 and 12 of the window frame.

If desired, the outer side of the window frame may be fitted with a removable auxiliary frame 81, to one vertical edge of which is suitably hinged a screen 82 (see Figures 3 and 4), or a storm sash (not shown). This auxiliary screen or storm sash is so hinged as to adapt it to be swung inwardly of its supporting frame 81, it being understood, of course, that this inward swinging of the auxiliary frame is effected only when the sashes 14 and 15 are both swung into their open position as shown in Figure 4. Such an auxiliary frame

and its cooperating screen or storm sash is more specifically shown in my prior Patent No. 2,221,515, hereinbefore referred to, it being apparent that the construction of the present invention is adapted to receive such screen and/or storm sash assembly in essentially the same manner as does the construction of my said prior patent.

It will be understood, of course, that the invention is susceptible of various changes and modifications from time to time without departing from the real spirit or general principles thereof and it is accordingly intended to claim the same broadly, as well as specifically, as indicated by the appended claims.

- 15 1. In a window construction, in combination, a main frame, a pair of double counter-balanced sashes slidably mounted therein, means permitting said sashes to be swung inwardly of the frame about hinges respectively secured to opposite sides of said frame simultaneously as said sashes are disconnected from their respective counter-balancing devices, spring-pressed detents for connecting said counter-balancing devices to said frame automatically as said sashes are swung out of their normal planes of sliding movement, said frame being provided in the opposite sides thereof with sash-guiding channels and said channels being vertically recessed to accommodate said spring-pressed detents and means operatively associated with each detent for detachable engagement with opposite sides of each sash for normally connecting the latter to its opposed counter-balancing devices, the opposite edges of each sash being provided with blind recesses for receiving said last-mentioned means and concealing the same from external view when the sashes are in their normal sliding positions.
- 20 2. In a window construction, in combination, a main frame, a pair of double counter-balanced sashes slidably mounted therein, means permitting said sashes to be swung inwardly of the frame about hinges respectively secured to opposite sides of said frame simultaneously as said sashes are disconnected from their respective counter-balancing devices, spring-pressed detents for connecting said counter-balancing devices to said frame automatically as said sashes are swung out of their normal planes of sliding movement, said frame being provided in the opposite sides thereof with sash-guiding channels and said channels being vertically recessed to accommodate said detents, a fixed anchorage for said last-mentioned means projecting from the base wall of each of said vertical recesses in the sash-guiding channels, and means operatively associated with each detent for detachable engagement with opposite sides of each sash for normally connecting the latter to its opposed counter-balancing devices, the opposite edges of each sash being provided with blind recesses for receiving said last-mentioned means and concealing the same from external view when the sashes are in their normal sliding positions.
- 25 3. In a device for effecting automatic quick-detachable connection between a sliding window sash and a sash-balancing mechanism therefor, a main body member having means for permanent securement to one end of a sash-balancing mechanism and additional means for disengageable securement to one side edge of a window sash, said latter means including a projecting element on said body member adapted for accommodation within a blind notch formed in the inner surface of the window sash adjacent said side

edge thereof, and a spring-pressed anchoring element pivoted to said main body member and having a normal bias tending to press the lower free extremity thereof away from said edge of the sash and into engagement with a fixed element on the window frame.

4. In a device for effecting automatic quick-detachable connection between a sliding window sash and a sash-balancing mechanism therefor, a main body member having means for permanent securement to one end of a sash-balancing mechanism and additional means for disengageable securement to one side edge of a window sash, said latter means including a projecting element on said body member adapted for accommodation within a recess formed in the inner surface of the window sash adjacent the said side edge thereof, and a spring-pressed anchoring element pivoted to said main body member and

having a normal bias tending to press the lower free extremity thereof away from said edge of the sash and into engagement with a fixed element on the window frame, said spring-pressed detent being normally rotated about its pivot out of engagement with said fixed element when said sash is connected to said member by said co-acting projecting element and notch.

5. In a device of the character defined in claim 4 wherein said spring-pressed detent is provided with a cam-edged head adapted for engagement by said side edge of the sash when the latter is swung laterally into its vertical plane of sliding movement to automatically effect disengagement of said detent from said fixed element simultaneously as said sash and body member are connected together.

HARRY GOLDENBERG.
